UNITED STATES PATENT OFFICE.

EDGAR S. HOYT, OF DES MOINES, IOWA.

MACHINE FOR APPLYING TAPE.

1,399,715.

Specification of Letters Patent.

Patented Dec. 6, 1921.

Application filed June 21, 1920. Serial No. 380,840.

To all whom it may concern:

Be it known that I, EDGAR S. HOYT, a citizen of the United States, and resident of Des Moines, in the county of Polk and State 5 of Iowa, have invented a certain new and useful Machine for Applying Tape, of which the following is a specification.

My invention relates to machines for applying tape to linoleum, congooleum, oil-10 cloth and the like.

The object of my invention is to provide a simple, inexpensive portable machine which may be manually manipulated for applying tape to linoleum and other ma-15 terials.

A further object is to provide such a machine having a pressure roller, a supporting roller and a magazine roller with suitable guides and with means for applying 20 adhesive material to a tape.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a side elevation of a machine embodying my invention.

Fig. 2 shows a top or plan view of the same; and

Fig. 3 shows a detail view, partly in section, taken on the line 3—3 of Fig. 1, of the 35 magazine roller or drum or spool which carries the tape.

My improved machine comprises a pair of horizontally spaced parallel frame members 10, having their ends connected by 40 axles. These axles comprise headed bolts 11 having smooth portions 11^a, collars 11^b adjacent thereto, and screw-threaded portions 11^c. Each bolt 11 is screwed into one end of a tubular axle 11^d.

Above the central portion of the machine 45 is a handle 12, mounted on a spindle or the like 13, having a head 14 and removable nut 15. Mounted on each end of the spindle 13 is a frame member 16, extending downwardly. The lower portions of the frame members 16 have bifurcated arms 17, inclined slightly away from each other and

connected with the ends of the respective frame members 10, as illustrated in Figs. 1 and 2.

Mounted on the forward tubular axle 11^d is the hub 18 of a drum or spool having a series of spaced flanges 19. Mounted between each pair of flanges 19 is a roll of tape 20, which is preferably gummed on one 60 side and may be provided with any kind of indicating characters 21, preferably representing units of measure.

On the rearward tubular shaft 11^d is mounted a roller 22, which is a supporting 65 and tape pressure roller.

Extending downwardly from the frame members 10, near the spool or drum 19, are arms 23, which are connected by a shaft 24 on which is a smaller supporting roller 25. 70

Extending downwardly from the shaft 24 is a guide arm 26, and extending downwardly from one of the bolts 11 at the forward part of the machine is a guide arm 27. Secured to one of the arms 17 is a 75 spring tension member 28, adapted to frictionally engage the side of the spool 19, as illustrated particularly in Figs. 1 and 2, for imposing tension on the spool.

Mounted between the members 10 is a reservoir 29, for water, paste, glue or the like. Supported by the members 10 is a spindle 30, on which is a moistener roller 31. The end of one of the tapes 20 is threaded from the drum 19 over the moistener roller 31, thence 80 downwardly under the pressure roller 22.

Pivotedly secured to the rear arms 17 are arms 32, which support a roller 33 between their outer ends for smoothing the tape and finishing the application of the tape 90 to the lineoleum. Various suitable forms of smoothing and finishing devices could be used. The arms 32 are connected by a cross member 34.

I find that the application of the tape can 95 usually be made without the roller 33, but I employ it to insure perfect results in all cases. A spring 35 is secured to an arm 32 and one of the members 10. This spring serves to impose proper tension for holding the roller 33 in operative position. When the arms 32 are swung upwardly to position nearly parallel with the adjacent arms 17, the spring will be swung over center and

will hold the arms 32 in their raised position.

In the practical use of my improved machine for applying tape, the linoleum or the like 32 in the factory is laid out on long tables for inspection. The strip of tape 20 is threaded through the machine as heretofore explained, and one end thereof is pasted to the linoleum or the like at one end thereof. The handle 12 may then be grasped, and my machine may be pushed along the table, traveling on the linoleum. The tape 20 will be supplied with adhesive material, or, if gummed, will be supplied with water, from the reservoir 29 by means of the roller 31, and the gummed surface of the tape will be pressed against the linoleum by the pressure roller 22.

The linoleum may then be rolled up, preferably beginning at the end which has the tape with the largest figure on, and a measuring tape will be found on the linoleum.

The advantages of such a machine, and of applying the tape to the linoleum, will be largely obvious from the foregoing description.

It is well-known that linoleum and similar products are rather bulky and heavy to handle in the retail store, and by the use of tape applied by my machine, the linoleum need not be measured, but the length thereof can readily be estimated from the figures on the tape.

It is also well-known that frequently, after part of a roll of linoleum has been used, it is impossible to tell how much is left in the roll without opening and unrolling the roll and measuring it. Where my tape is employed, the salesman can always look at the end of the roll of linoleum and ascertain in an instant how much of the roll is left.

The saving of time to be accomplished with a machine of this kind is obvious.

Some changes may be made in the construction and arrangement of the various parts of my improved machine for applying tape, and it is my purpose to cover by my claims any improvements or modifications of structure or use of mechanical equivalents, which may be reasonably included within their scope.

I claim as my invention:

1. In a portable tape applying machine, a frame, supporting rollers thereon, a tape smoother member movably mounted on said frame, a spool on said frame, a moistener device interposed between said smoother member and said spool and a device for imparting tension to said smoother member.

2. In a machine for applying tape, a frame, including laterally spaced members, a tubular axle, spindle members mounted in the ends of said tubular axle and in said frame, a spool mounted on said tubular axle,

having a series of laterally spaced flanges, a pressure roller mounted on said frame, and a supporting roller mounted on said frame.

3. In a machine for applying tape, a frame, including laterally spaced members, a tubular axle, spindle members mounted in the ends of said tubular axle and in said frame, a spool mounted on said tubular axle, having a series of laterally spaced flanges, a pressure roller mounted on said frame, a supporting roller mounted on said frame, and guide arms adapted to engage a support on which the machine travels for causing tape to be applied parallel with the edge of said support.

4. In a machine for applying tape, a frame, including laterally spaced members, a tubular axle, spindle members mounted in the ends of said tubular axle and in said frame, a spool mounted on said tubular axle, having a series of laterally spaced flanges, a pressure roller mounted on said frame, a supporting roller mounted on said frame, and a moistener device supported upon said frame between said spool and said pressure roller.

5. In a machine for applying tape, a frame, including laterally spaced members, a tubular axle, spindle members mounted in the ends of said tubular axle and in said frame, a spool mounted on said tubular axle, having a series of laterally spaced flanges, a pressure roller mounted on said frame, a supporting roller mounted on said frame, a moistener device supported upon said frame between said spool and said pressure roller, and a friction tension device on said frame for coacting with said spool.

6. In a portable tape applying machine, a frame, a supporting roller thereon, a spaced movable smoother member on said frame, a spool on said frame, a moistener device on the frame interposed between the smoother member and said spool, and a tension device on said spool.

7. In a device of the class described, a frame, comprising an upper, central, handle member, frame members extending respectively downwardly and rearwardly and downwardly and forwardly therefrom, a frame structure connecting the lower ends of said first frame members, a tape pressure and a supporting roller mounted for rotation at the lower end of one of said first described frame members, supporting means projecting downwardly from said connecting frame member, a supporting roller on said supporting means, a spool mounted for rotation on said frame, and a moistener device supported on said frame and interposed between said spool and said pressure roller.

8. In a device of the class described, a frame, a supporting roller 25 therefor, a spool mounted on said frame, a pressure roller 22 supported on said frame, a mois-

tener device interposed between said spool and pressure roller and a smoother device movably supported on said frame at the rear thereof.

5 9. In a device of the class described, a spool mounted thereon, a supporting roller for said frame, a second roller on said frame,

comprising a supporting and tape pressing roller, a moistener device interposed between said spool and said second roller, and a tape 10 smoothing device movably mounted on the rear portion of said frame.

Des Moines, Iowa, May 29, 1920.
EDGAR S. HOYT.
